UNITED STATES PATENT OFFICE.

COURTLAND SKINNER, OF CHICAGO, ILLINOIS, ASSIGNOR TO FREDERICK C. AUSTIN, OF SAME PLACE.

APPARATUS FOR SEPARATING MATERIALS BY CENTRIFUGAL FORCE.

SPECIFICATION forming part of Letters Patent No. 617,864, dated January 17, 1899.

Application filed December 7, 1896. Serial No. 614,740. (No model.)

To all whom it may concern:

Be it known that I, COURTLAND SKINNER, a citizen of the United States, residing at Chicago, in the county of Cook and State of Illinois, have invented a certain new and useful Improvement in Apparatus for Separating Materials by Centrifugal Force, of which the following is a specification.

My invention relates in general to centrifugal apparatus adapted for treating pulverized or granular masses composed of substances having different degrees of specific gravity so as to separate the heavier from the lighter ones; and it relates in particular to a variety of centrifugal apparatus in which the lighter particles of the outwardly-flying mass of material are stopped and carried back inwardly by an opposing fluid stream or current, while the heavier ones are allowed to continue their outward movement.

Prominent objects of my invention are to provide a simple, practical, and efficient apparatus of the class specified; to insure certainty and accuracy of action in the separating process; to arrange for the quick, effective, and accurate regulation of the machine with reference to materials having unlike differences between the degree of specific gravity of their heavier and lighter particles; to allow the operation of the apparatus under the most favorable and advantageous circumstances; to simplify its construction and reduce its cost of manufacture and maintenance, and to provide certain novel features and details serving to increase the general efficiency and utility of centrifugal separators.

In a centrifugal separator characterized by my invention a rotary receptacle adapted to receive and subject the materials to centrifugal force is immersed in a relatively stationary or non-rotative body of fluid. The rotary receptacle is provided with suitable passages through which the fluid is forced inwardly and in opposition to the outwardly-moving particles of material by suitable means independent of the means by which the material is projected outwardly, so as to permit of its degree of force being varied independently of the degree of centrifugal force to which the material is subjected. In this way, when different materials are treated, the

degree of centrifugal force can be maintained constant, while the force of the fluid stream or current can be easily and quickly adjusted to a degree intermediate between the degrees of force respectively imparted to the heavier and lighter substances of each material by their momenta, so as to effectively stop and carry back the latter without interfering with the former, or the degree of centrifugal force can be so varied as to cause the forces respectively possessed by the heavier and lighter substances of each material to differ to the extent most desirable for separation, and when so varied the degree of force of the fluid stream or current can be properly and relatively adjusted.

The fluid which is forced in opposition to the outwardly-moving particles of material could be a liquid, such as water, or it could be a gas, such as air or steam, although I find that in the form of apparatus which I have invented for carrying out my invention it is advantageous to slightly modify certain minor features, according as a liquid or a gas is employed. Therefore I have filed two applications for patents, this one, and another filed contemporaneously with this one and serially numbered 614,741, and have described in this one an apparatus having the minor details particularly fitting it to utilize a liquid current or stream, and in the other one a similar apparatus having the minor details particularly fitting it to utilize a gaseous current or stream, and have chosen to embody in this application the broad or generic claims of my invention. Hence it will be understood that while I herein use the term "liquid" the broader features of the invention adapt it for use with a gas as well, as will be observed by reference to my other said application.

In the accompanying drawings, Figure 1 is a side elevation of a separating apparatus embodying my invention. Fig. 2 is a vertical section of the separator in which the separating process occurs, taken on a plane passing through the axis of rotation of its treatment-chamber. Figs. 3 and 4 are horizontal sections taken on lines 3 3 and 4 4, respectively, in Fig. 2. Fig. 5 is a section similar to Fig. 2, showing a preferred form of sepa-

rator. Fig. 6 is a horizontal section taken on line 6 6 in Fig. 5. Fig. 7 is a vertical section, taken on an enlarged scale, of certain details of construction embodied in the arrangement illustrated in Fig. 5; and Fig. 8 is a vertical section of a separator having a modified arrangement for recovering the heavier particles of material.

The material to be treated—such, for instance, as mineral-ore pulp—is usually mixed with water or other suitable liquid, so that it can be readily fed into the treatment-chamber and can be prevented from objectionably flying about when finely ground. The mixture thus formed is desirably confined preparatory to treatment in a suitable reservoir A, Fig. 1, which latter is conveniently mounted upon a standard or support A², and it flows from such reservoir A by way of a suitable delivery feed-pipe A', attached to the lower end thereof. It is fed by the feed-pipe A' into the rotary treatment-chamber provided by a rotary receptacle B², (see Fig. 2,) a convenient arrangement therefor being to arrange a laterally-extending end portion of the feed-pipe A' within a suitable opening at the top of the receptacle B², and to extend the same downwardly nearly to the bottom or floor of such receptacle. In this way the efficient and uniform distribution of the material within the treatment-chamber is assured. The material thus delivered to the rotary treatment-chamber is projected outwardly from the axis of rotation of the receptacle B² in opposition to a liquid current or stream which is forced into and inwardly within a surrounding liquid-receiving chamber conveniently provided by a vertically-arranged inclosing shell or casing B'—as, for example, by way of a suitable liquid-supply pipe C', attached to the upper end of the shell B'—and thence into the treatment-chamber provided by the receptacle B² by way of suitable side openings with which the latter is provided. As a result the particles of the lighter substance are stopped at the side openings in the receptacle B² and carried back within the latter, while those of the heavier substance continue their movement in an outward direction through the side openings in the receptacle B² and into the liquid-receiving chamber provided by the shell or casing B'. In this way it will be seen that either the degree of centrifugal force to which the material is subjected or the opposing fluid force can be independently regulated or varied so as to sustain any desired relation to the other by varying either the speed of rotation of the receptacle B² or the pressure under which the fluid is supplied, and also that both of the same can be simultaneously varied so as to allow either one to be given a desired degree and the other to sustain any given relation to it after it has been adjusted to such degree by simultaneously regulating or adjusting the speed of rotation and the degree of fluid-pressure. For example, the fluid-

pressure can be regulated with reference to different materials—that is to say, materials having unlike differences between the degrees of specific gravity of their heavier and lighter substances—while the speed of rotation is maintained constant, or the speed of rotation can be varied while the fluid-pressure is maintained constant, or both the speed of rotation and the degree of fluid-pressure can be regulated simultaneously, but in unlike amounts. Consequently I am enabled to successfully treat all grades of material and to treat them all in the most efficient and effective manner and under the most advantageous circumstances, it being observed that each grade of material must be subjected to a degree of centrifugal force sufficient to establish between its heavier and lighter substances such a difference of momentum as to allow their ready and accurate separation. While this rotary receptacle B² could of course be of any suitable construction and could be provided in any suitable way with openings for permitting the escape from within of the heavier particles of material and also for allowing the entrance of the opposing liquid stream or current, I prefer the arrangement and construction shown in the drawings and consider that they constitute matters of further and specific improvement.

The receptacle shown comprises a flat disk-shaped top B⁴, having an opening for the feed-pipe A', a bottom B⁵, and a series of long slats b², extending between said bottom and top and arranged in circular form within the outer edges of the top B⁴ and bottom B⁵, so as to leave a protected space intervening between the circular treatment-chamber wall which they form and the wall of the shell or casing B'. This space allows the liquid entering the liquid-chamber by way of the pipe C' to circulate to an extent to acquire an even and uniform inward force before entering the treatment-chamber. The outer edges of the top B⁴ and the bottom B⁵ of the receptacle are desirably extended outward nearly to the walls of the shell or casing B', whereby the water entering through the pipe C' is not directed immediately against the rotating receptacle, and also whereby particles of matter are prevented from falling until they reach the vicinity of the walls of the shell or casing B'. These slats b² are situated at such distances apart as to form intervening longitudinal side openings b', extending from top to bottom of the receptacle. They are also desirably inclined transversely from radial directions, so that the openings b' are transversely non-radial and so allow the easy exit of the heavy particles and the entrance of the water or other liquid during rotation. Said slats b² are also desirably constructed with pointed inner vertical edges, so that the particles of material are not only prevented from collecting upon the inner edges of said slats, but are allowed to move freely outward into the intervening openings. The compar-

atively thick outer edges of the slats b^2 are desirably situated close together, so that the intervening openings b' are outwardly contracted to an extent to form long narrow en- 5 compassed and well-defined openings. These openings permit the opposition of the inflowing liquid stream or current to the outwardly-flying particles of material to occur at a fixed distance from the axis of rotation and in such 10 a comparatively small and nearly encompassed region that while the heavier particles can pass easily out of the treatment-chamber and into the inclosing fluid-chamber the lighter ones are accurately chosen and effect- 15 ively stopped and washed back into the treatment-chamber. The slats b^2 can be arranged in cylindrical form, as shown in Figs. 2 and 3, or they can be arranged so as to flare or diverge upwardly, as shown in Figs. 5 and 6, it 20 being observed that in either case they are circularly arranged. Of the two arrangements I prefer the latter, for the reason that in it the momentum of the outwardly-flying particles is proportioned to the force of the 25 inflowing liquid current or stream—that is to say, the momentum of the particles is greatest at the upper end of the treatment-chamber, where the force of the liquid stream is greatest, owing to the pipe C' being attached to the 30 upper end of the shell or casing B' , and it gradually diminishes in a downward direction in accordance with the decrease in the force of the liquid stream as the distance from its 35 point of entrance is increased. The rotary receptacle thus formed is conveniently mounted for rotation at the upper end of a rotary driving-shaft E , having a pulley E' and working in suitable bearings e' and e , formed, respectively, in the bottom of the shell or casing B' and on the lower portion of a suitable 40 frame D , which supports the latter.

The liquid stream or current forced into the rotary treatment-chamber is conveniently allowed to leave the same by way of the opening formed in the top B^4 and receiving the end of the material feed-pipe A' and also by way of a cylindric extension or hollow journal B^6 , which is desirably formed at the upper end of the receptacle B^2 and around the 45 opening in the top B^4 and which serves as an upper journal for the receptacle. As a simple arrangement for draining the liquid stream thus arising from the treatment-chamber I have shown an annular vessel B^8 , arranged above the casing B' and around the upper end of the cylindric extension B^6 and having an internal opening B^9 , whose lower edge registers with the upper edge of the latter, and having also a spout B^7 extending 50 downwardly from its outer periphery.

The heavier particles of material after passing out of the treatment-chamber into the liquid-chamber provided by the casing B' continue to move outwardly in the latter until 55 they reach the region of quiet near the walls of the casing B' and there fall to the bottom of the same, where they are first received by

the marginal portion of the disk B^5 , which latter will tend to drive them by centrifugal force to its outer edge, where they will again fall and be collected by any suitable device. As an arrangement for withdrawing or recovering such heavy particles I have shown in Fig. 2 a removable pan or drawer H , arranged between a horizontal shelf B^9 , having 70 circumferential openings b^9 , and the bottom or floor of the shell or casing B' . As another arrangement I have shown in Fig. 8 a chamber H' , situated below the shelf B^9 and having a spout H^2 , which is provided with a valve or cock h^2 . By this latter arrangement there can be withdrawn from the separator a sufficient quantity of the liquid to remove the heavy particles settling in the chamber H' . Such latter arrangement is desirable for the 85 reason that it permits the continuous operation of the separator, while in the former arrangement the action must be stopped and the liquid drawn off in order to allow the withdrawal of the pan or drawer B^9 . 90

In the arrangement shown in Fig. 8 the shaft E is shown confined within a sleeve E^2 , which extends in an upward direction substantially to the shelf B^9 , whereby the particles of material within the chamber H' are 95 not subjected to centrifugal force, which would otherwise result from the rotation of such shaft.

The space between the walls of the casing B' and the walls of the rotary receptacle B^2 , which space serves as a space for receiving the heavy particles preparatory to their recovery, can, if desired, be provided with a series of radially-extending walls or portions b^{10} , Figs. 5 and 6. These will serve to prevent any rotation of the liquid in such space, and will thereby serve to allow the heavy particles to fall quickly and unmolested to the bottom of the liquid-chamber.

The particles of material can be prevented 100 from settling upon the bottom or floor B^5 of the treatment-chamber by forcing liquid upward through a series of upwardly-directed openings or passages, such as b^5 , Fig. 7, formed in such floor. These openings or 105 passages b^5 can be situated near the outer edge of the chamber floor and can be inwardly inclined, whereby a very few of them will admit liquid enough to lift the particles. The liquid can be conveyed to these openings b^5 110 by way of the rotary supporting-shaft E , which can for such purpose be constructed with a longitudinal bore E^4 . When thus constructed, it can be connected with the receptacle by means of a hollow casting, whose 115 chamber E^6 can serve as a medium of communication between the openings b^5 and the bore E^4 of the shaft E . The shaft E can in such case be mounted at its lower end in a suitable water-tight bearing, and the latter 120 can be connected with a suitable liquid-supply by means of a pipe E^5 . This portion of the apparatus B , comprising the rotary receptacle B^2 , the inclosing shell or casing B' , 125

and adjuncts, I conveniently term the "separator" for the reason that the separating process occurs in it.

The liquid stream or current can be forced into the separator by any suitable means adapted for supplying liquid under pressure and capable of being regulated so as to vary such pressure. For instance, a closed liquid-tank C, Fig. 1, can be attached to the pipe C', leading to the separator B, and can be supplied with liquid from any suitable source by means of a pipe C². The liquid in the tank C can thus be subjected to any desired degree of pressure—as, for instance, by forcing air or other gas under pressure into the tank through a pipe C, attached to its upper end and connected with suitable means for supplying air or the like under pressure, which may be assumed to be present.

It is obvious that where the particles in a given mass of material are substantially equal in size the heavier will be separated from the lighter. It is not so clear, however, that separation will take place should the particles happen to be of "equal falling sizes." By "equal falling sizes" is meant such sizes as will permit particles to fall the same distance through a given medium, notwithstanding a difference in the specific gravity of such particles. Hence it will be shown mathematically that separation will occur in such case also. Take, for example, a mass of material composed principally of iron pyrites and quartz. The specific gravities of these ingredients are known to be 4.9 and 2.6, respectively, and spheres thereof having diameters bearing the ratio of one and two-thirds to four, respectively, are known to be equal falling sizes in water. Let the speed imparted to the particles by the rotation of the rotary receptacle be designated by the letter S and the water-pressure by the letter P. Then the momentum in each case will be the product of the volume, the specific gravity, and the velocity—that is, in the case of the pyrites $(\frac{5}{3})^3 \times 4.9 \times S$, or 22.7S, and in the case of the quartz $(4)^3 \times 2.6 \times S$, or 41.6S. The opposing force in each case will be the product of the surface exposed by each particle into the water-pressure—that is, in the case of the pyrites $(\frac{5}{3})^2 \times P$, or 2.8P; and in the case of the quartz $(4)^2 \times P$, or 16P. Now in order to cause separation, the momentum of the particles of pyrites must be greater than the water force opposing the movement and the momentum of the particles of quartz must be less than the water force opposing their movement—that is, 22.7S 2.8P and 41.6S 16P, or, inverting the latter, 16P 41.6S. Now if a true arithmetical inequality can be obtained from these two inequalities the proposition will be established. To such end multiply together the latter when considered in the same sense, and the result will be 363.2SP 116.48SP. Then remove the constant SP from both sides, and the true arithmetical inequality 363.2 116.48 remains, thus establishing

the operativeness of the process for equal falling sizes. In order to determine the ratio which the velocity of the particles and the water-pressure must bear to each other in this case, reduce the original inequalities to their simplest forms in terms of P; thus, 8.1S P and 2.6S P. That is to say, for a mass of material composed of pyrites and quartz the water-pressure must be between 2.6 and 8.1 times the velocity imparted to the particles when such factors are expressed in any absolute system of measurements.

What I claim is—

1. In a separator in which the materials are separated by the coöperation of centrifugal force and an opposing fluid-current, a rotary receptacle for subjecting the materials to centrifugal force immersed in a non-rotative body of fluid, said receptacle being provided with one or more passages wherein the said materials and fluid will meet in opposition; a suitable tank or receptacle for inclosing or holding said body of fluid; independent means for forcing said fluid inwardly through said passages in opposition to the outwardly-moving materials, and means for varying such fluid-pressure independently of and without varying the speed of the rotary receptacle; the said rotary receptacle being adapted and arranged for an independently-variable rotation, whereby the centrifugal force may be varied independently of and without varying the said fluid-pressure.

2. In a separator in which the materials are separated by the coöperation of centrifugal force and an opposing fluid-current, an outer stationary shell or casing forming an exterior inclosing chamber; a rotary receptacle for subjecting the materials to centrifugal force, inclosed within said stationary shell or casing, and having side openings; means for supplying the rotary receptacle with the materials to be separated; means for rotating said receptacle; means for supplying fluid under pressure to said stationary inclosing chamber, and means for discharging or carrying off the fluid and lighter particles of matter; the said side openings in the rotary receptacle being adapted to afford passages, wherein the said materials and fluid will meet in opposition; the relatively heavy particles of matter being allowed to pass out into the stationary chamber, while the relatively light particles are carried back into the rotary receptacle, and, with the fluid, discharged from the separator, substantially as described.

3. In a separator in which the materials are separated by the coöperation of centrifugal force and an opposing fluid-current, the combination of a rotary receptacle adapted to receive and subject the materials to centrifugal force, and having side openings or passages in which the said materials and fluid will meet in opposition; a relatively stationary fluid-chamber inclosing the said rotary receptacle; means for supplying fluid under pressure to said stationary chamber; and

means adapted to prevent the rotation of the fluid in said stationary chamber, substantially as described.

4. In a separator in which the materials are separated by the coöperation of centrifugal force and an opposing fluid-current, a rotary receptacle immersed in a non-rotative body of fluid and adapted to receive and subject the materials to centrifugal force; said receptacle having upwardly flaring or divergent side walls provided with outwardly-contracted openings adapted to form passages wherein the said materials and fluid will meet in opposition; a suitable tank or casing for inclosing said body of fluid, and means for forcing the said fluid inwardly through said passages in opposition to the outwardly-moving materials.

5. In a separator in which the materials are separated by the coöperation of centrifugal force and an opposing fluid-current, a rotary receptacle immersed in a non-rotative body of fluid and adapted to receive and subject the materials to centrifugal force; said receptacle having upwardly flaring or divergent side walls provided with outwardly-contracted openings separated from one another by inwardly-reduced or wedge-like partitions, the said openings being adapted to afford passages wherein the said materials and fluid will meet in opposition; a suitable tank or receptacle for holding said body of fluid, and means for forcing said fluid inwardly through said passages in opposition to the outwardly-moving materials.

6. In a centrifugal separator in which the materials are separated by the coöperation of centrifugal force and an opposing fluid-current, a rotary receptacle adapted to subject the materials to centrifugal force, and having upwardly flaring or divergent side walls provided with tangential and outwardly-contracted openings; and means for supplying fluid under pressure; the said openings being adapted to afford passages in which the said materials and the said fluid will meet in opposition, substantially as and for the purpose described.

7. In a centrifugal separator, a rotary material-receiving chamber for subjecting the materials to centrifugal force and having one or more passages; a relatively stationary or non-rotative body of fluid surrounding said rotary receptacle, and independent means for forcing said fluid inwardly through said passages in opposition to the centrifugally-projected materials; the said rotary receptacle being also provided at its top with an outlet for discharging both the said fluid and lighter particles of matter.

8. In a centrifugal separator, a rotary material-receiving chamber having annular externally-arranged upper and lower flanges, the former adapted to deflect and regulate the flow of fluid under pressure, and the latter arranged to receive and direct the heavy particles of matter after separation and prepara-

tory to recovery; means for supplying fluid under pressure located at a point above the said upper flange, and means for placing the said fluid in opposition to the materials at a time when the latter are subjected to centrifugal force, substantially as described.

9. In a separator, in which the materials are separated by the coöperation of centrifugal force and an opposing fluid-current, a rotary material-receiving chamber comprising upper and lower disks forming top and bottom flanges respectively, and side walls composed of vertical slats or the like arranged to provide, in effect, openings or passages in which the said materials and fluid will meet in opposition; the said upper disk being adapted to deflect and regulate the flow of fluid under pressure, and the lower disk being arranged to receive and direct the heavy particles of matter after separation and preparatory to recovery, substantially as described.

10. In a separator, in which the materials are separated by the coöperation of centrifugal force and an opposing fluid-current, a rotary material-receiving chamber comprising upper and lower disks and intermediate side walls composed of slats, or the like; the said slats being arranged to provide openings or passages in which the said materials and fluid will meet in opposition, and the said upper disk being provided with an opening; a hollow journal communicating with the opening in said upper disk, and adapted to provide an upward discharge-passage for the said fluid and lighter particles of matter, and a stuffing-box for said hollow journal, substantially as described.

11. In a separator in which the materials are separated by the coöperation of centrifugal force and an opposing fluid-current, a rotary material-receiving chamber adapted to subject the materials to centrifugal force, and having its lower end or floor provided with fluid-inlet openings, and means, independent of the main fluid-supply, for forcing fluid through said inlet-openings, thereby preventing the materials from settling or accumulating on the floor of the said rotary chamber, substantially as described.

12. In a separator in which the materials are separated by the coöperation of centrifugal force and an opposing fluid-current, a rotary material-receiving chamber having its lower end or floor provided with upwardly-directioned inlet-openings; a rotary shaft connected with said chamber and having a bore communicating with said inlet-openings; and means for forcing fluid, through said shaft and openings, into said chamber for the purpose of preventing the materials from settling on the floor of said rotary chamber, substantially as described.

13. In a separator in which the materials are separated by the coöperation of centrifugal force and an opposing fluid-current, the combination of a rotary receptacle providing

- 5 a rotary treatment-chamber, and a relatively stationary fluid-chamber inclosing the rotary receptacle and provided with radially-disposed stationary walls or partitions extending outwardly from the side walls of the said receptacle; the said radial partitions being adapted to prevent rotation on the part of the fluid in said inclosing chamber, substantially as described.
- 10 14. A centrifugal separator comprising an outer stationary inclosing shell or casing, providing an exterior chamber adapted for primarily receiving and containing fluid under pressure, and also for receiving the comparatively heavy particles of material preparatory to recovery; and an internally-arranged rotary receptacle inclosed within said shell or casing and providing a centrifugal treatment-chamber having its upper end provided with
- 15 an opening adapted to serve both as a material-inlet and a fluid-outlet; said rotary receptacle also having its side walls provided with openings adapted to serve both as inlets for the fluid and as outlets for the comparatively heavy particles of material, as set forth.
- 20 15. A centrifugal separator comprising an outer stationary inclosing shell or casing, providing an exterior chamber adapted for primarily receiving and containing fluid under pressure, and also for receiving the comparatively heavy particles of material preparatory to recovery; an internally-arranged rotary receptacle inclosed within said shell or casing and providing a centrifugal treatment-chamber having its upper end provided with an opening adapted to serve both as a material-inlet and a fluid-outlet, and having its side walls provided with openings adapted to serve both as inlets for the fluid and as outlets for the comparatively heavy particles of material; and means for withdrawing the said comparatively heavy materials from the outer chamber, substantially as described.
- 25 16. In a separator in which the materials are separated by the coöperation of centrifugal force and an opposing fluid-current, a ro-

tary receptacle adapted to subject the materials to centrifugal force and having its lower end or floor provided with inlet-openings, and means for forcing fluid into the receptacle by way of said opening for the purpose of agitating the materials and preventing the same from settling or accumulating upon the said floor, substantially as described.

17. In a separator in which the materials are separated by the coöperation of centrifugal force and an independent opposing fluid-current, a rotary receptacle adapted to subject the materials to centrifugal force and having side walls provided with openings or passages wherein the said materials and fluid will meet in opposition; the base of said receptacle being extended to provide an annular flange adapted to receive and direct the heavy particles of matter after separation and preparatory to recovery; the said flange forming practically the floor or bottom of the outer stationary fluid-chamber, and having sufficient space between its outer edge and the casing to permit the heavy particles of material to pass downwardly to a collecting-receptacle, substantially as described.

18. In a centrifugal separator in which granular materials are separated by the coöperation of centrifugal force and an opposing fluid-current, a rotary material-receiving chamber adapted to subject the materials to centrifugal force, and having side openings or passages wherein the said materials and fluid will meet in opposition, and also having an annular externally-arranged flange above said side openings, adapted to deflect and regulate the flow of fluid under pressure; a stationary chamber inclosing said rotary receptacle, and a fluid-supply inlet, located above said flange, for supplying said stationary chamber with fluid under pressure, substantially as described.
